CLAIM

The ornamental design for a safety belt for cars, as shown and described.

DESCRIPTION

FIG. 1 is a perspective view of a safety belt for cars showing my new design;

FIG. 2 is a front elevational view thereof;

FIG. 3 is a top plan view thereof;

FIG. 4 is a bottom plan view thereof;

FIG. 5 is a left side elevational view thereof; and

FIG. 6 is a rear elevational view thereof.

The broken line showing of the partial interior of a car is for illustrative purposes only and forms no part of the claimed design.

FIG. 1

FIG. 2

FIG. 3

FIG. 4

FIG. 5

FIG. 6
